UNITED STATES PATENT OFFICE.

NELSON M. BAKER, OF SOUTHBIDGE, MASSACHUSETTS, ASSIGNOR TO AMERICAN OPTICAL COMPANY, OF SOUTHBIDGE, MASSACHUSETTS, A CORPORATION OF MASSACHUSETTS.

DESIGN FOR A NOSE-GUARD.

44,230.

Specification for Design.

Patented June 24, 1913.

Application filed March 7, 1912. Serial No. 682,266. Term of patent 14 years.

To all whom it may concern:

Be it known that I, NELSON M. BAKER, a citizen of the United States, residing at Southbridge, in the county of Worcester and State of Massachusetts, have invented a new, original, and ornamental Design for Nose-Guards, of which the following is a specification, reference being had to the accompanying drawings, forming a part thereof.

Figure I represents a plan view of my improved design for nose glass guard. Fig.

II represents a side elevation of said design particularly illustrating the shepherd's crook shape of the main guard member with the supplemental pad attached to the terminus of the crook.

I claim:

The ornamental design for a nose guard, substantially as shown.

NELSON M. BAKER.
